UNITED STATES PATENT OFFICE.

RICHARD ALEXANDER McLAURIN, OF MILLIKENPARK, SCOTLAND.

GUMMED PAPER AND PROCESS OF MAKING THE SAME.

No. 890,570.

Specification of Letters Patent.

Patented June 9, 1908.

Application filed February 23, 1907. Serial No. 358,877.

To all whom it may concern:

Be it known that I, RICHARD ALEXANDER McLAURIN, of Cartside Mills, Millikenpark, in the county of Renfrew, Scotland, paper-maker, have invented certain new and useful Improvements in Gummed Paper and Processes of Making the Same, of which the following is a specification.

This invention relates to a process for the manufacture of gum paper and the like, such as gummed cloth, or stay papers for paper box making, and consists of a new or improved process for producing slight indentations, incisions, minute recesses or roughnesses over the entire surface of the gum, mucilage or like adhesive material applied to the surface of the paper to break up the surface tension of the gum. By this method of treatment the following advantages are obtained. The roughened surface causes the paper to adhere more firmly to any smooth or textile surfaces. Gum papers or the like so treated are more easily fed to lithographic or other printing machines owing to the air cushion provided by the numerous indentations, obviating the usual tendency of such to adhere to one another, and the liability of setting off after printing is also minimized, and for the same reason there is less liability to stick together when the gummed paper is subjected to the action of damp. It is also found that gum paper so treated lies flatter in the sheet and has not the same tendency to curl up as is usually the case with untreated gum papers, particularly when in the form of gum tickets. Also stay papers and cloths such as are used for edgings in paper box making are rendered more soft and pliable and therefore more easily applied.

In order that my invention may be properly understood I have hereunto appended a diagrammatic drawing illustrating one method and means for carrying the process into effect or practice.

In carrying into practice the improvements of this invention the gum paper in sheets or long lengths or it may be in the form of fashioned articles is passed under pressure between a pair of rollers, one of which is etched or engraved with a suitable design, or it is acted on by a similarly engraved plate in a press.

When rollers are employed one of them is plain and the other is engraved or etched with a suitable design and acts on the

gummed side of the paper, cloths or the like. The gummed side of the paper is in contact with the plain roller and is therefore not affected by the design on the other roller to any appreciable extent.

It is obvious that various arrangements of rollers may be employed to produce the desired effect, but the diagrammatic drawing hereto appended illustrates one convenient arrangement. In this arrangement the dry gum paper *a* passes from the roller *b*, suitably mounted, between the engraved, etched or embossing metal or other roller *c* and the roller *d*, half round it and the next roller *e*. The rollers *d* and *e* may be paper rollers or be of any equivalent or suitable materials. The paper then passes between the paper or like roller *e* and the plain steel or other metal roller *f* and again between the paper or like roller *g* and another plain steel roller *h* whence it passes to the roller *i*. In passing between the rollers *e* and *f*, and *g* and *h*, the plain or ungummed side of the paper is acted on by the plain metal roller to smooth it and at same time flatten any slight markings of the engraved roller *c* which may pass through to the ungummed surface of the paper.

When a press is employed an engraved plate acts on the gummed surface while the ungummed surface of the paper lies on a smooth platen, the plate being formed to suit the articles being operated on which may be sheets, envelops, or other fashioned articles of gum paper or cloth.

The roller or plate may be engraved or etched with a design consisting of numerous crossed lines at very slight distances apart but any suitable design of such a sharp indented nature as will produce the desired effect may be employed.

What I claim as my invention, and desire to secure by Letters Patent is:—

1. The herein described process of treating gummed paper which consists in subjecting the same to pressure between a smooth surface and a sharply engraved surface, the gummed face of the paper being adjacent to the latter, whereby the gum on said surface is correspondingly roughened and its surface tension thereby eliminated, substantially as described.

2. The herein described process of treating gummed paper which consists in subjecting the same to pressure between a smooth surface and a sharply engraved surface, the

gummed face of the paper being adjacent to the latter, whereby the gum on said surface is correspondingly roughened and its surface tension thereby eliminated, and subsequently 5 calendering the paper to remove any resulting marks upon the ungummed surface of the paper, substantially as described.

3. As a new article of manufacture, gummed paper having the surface of the

gum roughened to eliminate the surface tension thereof, substantially as described. 10

In testimony whereof I have signed my name to this specification, in the presence of two subscribing witnesses.

Correction in Letters Patent No. 890,570.

It is hereby certified that in Letters Patent No. 890,570, granted June 9, 1908, upon the application of Richard Alexander McLaurin, of Millikenpark, Scotland, for an improvement in "Gummed Paper and Processes of Making the Same," an error appears in the printed specification requiring correction, as follows: In line 57, page 1, the word "gummed" should read *ungummed*; and that the said Letters Patent should be read with this correction therein that the same may conform to the record of the case in the Patent Office.

Signed and sealed this 6th day of October, A. D., 1908.
